[57] CLAIM

The ornamental design for the combined beverage support stand and blanket retainer, as shown and described.

DESCRIPTION

FIG. 1 is a perspective view of a combined beverage support stand and beach blanket retainer showing our new design;

FIG. 2 is a top plan view thereof;

FIG. 3 is a front elevational view thereof;

FIG. 4 is a right side elevational view thereof, with the left side view being substantially identical;

FIG. 5 is a rear elevational view thereof; and

FIG. 6 is a bottom plan view thereof.
